(57) **CLAIM**

The ornamental design of a trash can, as shown and described.

DESCRIPTION

This application is related to U.S. patent application Ser. No. 29/345,568 which is filed concurrently herewith.

FIG. 1 is an oblique view of a trash can showing my new design;

FIG. 2 is a side elevation view thereof;

FIG. 3 is side elevation view thereof, showing the side that is opposite the side shown in FIG. 2; and

FIG. 4 is a side elevation view thereof, showing a side that is 90° from the side shown in FIG. 2;

FIG. 5 is side elevation view thereof, showing the side that is opposite the side shown in FIG. 4;

FIG. 6 is a top plan view thereof; and,

FIG. 7 is a bottom plan view thereof.

The lid hinge is shown in broken lines for illustration purposes only and forms no part of the claimed design.
